(57) CLAIM

The ornamental design for a can compressor and storage
appliance housing with handle, as shown and described.

DESCRIPTION

FIG. 1 schematically illustrates a side view of a can compressor and storage appliance housing with handle; and,
FIG. 2 schematically illustrates a perspective view of the can compressor and storage appliance housing with handle of
FIG. 1.

The broken lines are for illustrative purposes only and form
no part of the claimed design.
